PACKING FOR FRAGILE ARTICLES

Morris Koppelman, Brooklyn, N. Y.,

Application April 11, 1933. Serial No. 665,485

19 Claims. (Cl. 229—87)

The improvements relate primarily to the packing of fragile articles, including glassware, china, porcelain, bottles and other containers, of various shapes and sizes, also to articles of any breakable material or of relatively frail construction, but they may be used for any purpose to which they are adaptable.

Packing made in accordance with the improvements is intended to be used in place of excelsior or the like, corrugated paper, tissue or other paper, felted pads and other packing material. Its objects are, among others, to provide a highly efficient packing for various uses in place of such other packing, which can be made by a simple process of manufacture of paper or wood pulp or similar raw material, preferably by the pulp-suction felting process in which forms having the shape and contour of the finished article are passed through a bath of loose fibres with suction behind the forms to draw the fibres against them and form a coating thereon which when removed and dried becomes the finished packing; to increase the strength and protective properties of packing of this general type and its adaptability 25 to various sizes and shapes of packed articles; to reduce the cost of manufacture, and to make the application of the packing to the article easier, simpler and more accurate.

The embodiment of the improvements contemplated 30 plates a packing manufactured in continuous extensible, contractible sheets having therein numerous plaits, folds or the like which are elastic and will exert tension when stretched or extended and pressure when compressed, due to the 35 character of the material and the form of the plaits made of such material and composing the packing sheets. These sheets may be made substantially flat in form or of conical or other shape. When made flat, they are adapted to 40 be cut to the desired length and formed into hollow cones, cylinders and other shapes by uniting their ends transversely, or they may be molded to the shape desired and used in their molded form, or inverted or turned inside out to produce 45 the form and shape desired. For the packing of articles of widely different shapes and sizes a number of units may be employed, but each unit will accommodate itself to numerous articles differing substantially in size, dimensions and con- 50 tour. Where the sheets made flat and joined together at their ends are used they may be first cut to different lengths to give different interior diameters, and such sheets may be made of different widths to accommodate articles of greatly 55 differing lengths, or a sheet of a given width may

be cut longitudinally to a lesser width or into two or more sheets for shorter articles. Where the units are molded complete in endless, conical or other convex form, they may be used as taken from the pulp mold or die, or molded in concave 60 conical or similar form and inverted to convex form to receive the article. In each and every case, however, the packing will form an elastic jacket or wrapping which will maintain itself in position enclosing the article and hold the article in position therein by its own resiliency, due to the fact that the article packed will exceed in circumference the normal internal circumference of the packing unit, so that when forced therein the former will cause the latter to stretch or expand and grip the said article. The packing is 65 also preferably made with the plaits or folds more or less curved lengthwise, so that its ends when it is applied to the article will have a tendency to contract and prevent the article from escaping 70 therefrom. The plaits are also in most cases tapered toward one end and provided at the other end, or at both ends, with inwardly projecting offsets, the first feature being adapted to make 75 the unit more yieldable at one end for the insertion of the article and the second to provide finger-like holding members to retain the article in position inside the packing unit and protect it against shocks and jars at its ends. While many 80 different sizes and shapes may be made, it is not necessary to make special shapes or sizes for ordinary articles or groups of articles, as it is not essential that the packing shall follow closely the size, shape or contour of the article owing to its 85 elasticity and resulting ability to accommodate itself to various sizes, shapes and contours. Thus a few packing units may be used to pack an entire set of china, one unit taking cups, saucers, and small plates, and another bowls, teapots, vegetable dishes and larger plates. Thus, also the 90 same unit may be employed for bottles of round, square, elliptical, and other cross section.

The improvements are illustrated in the accompanying drawings, in which—

Fig. 1 is an elevation of a packing embodying the improvements adapted for the packing of bottles and the like;

Fig. 2 is a perspective view of a portion of a packing sheet molded substantially flat;

Fig. 3 is a vertical, longitudinal section of the packing shown in Fig. 1 with a bottle therein;

Fig. 4 is a bottom end view of the packing of Figs. 1 and 3;

Fig. 5 is a top end view of the same;

Fig. 6 is a vertical cross section on the lines 110

6—6 of Fig. 3 looking in the direction indicated by the arrows in that figure;

Fig. 7 is a vertical cross section on the line 7—7 of Fig. 3 looking in the direction indicated 5 by the arrows in that figure;

Fig. 8 is a bottom end view of the packing of Fig. 1 applied to a bottle having a substantially rectangular cross section;

Fig. 9 is a bottom end view of the packing 10 of Fig. 1 applied to an elliptical shaped bottle;

Fig. 10 is a vertical medial section of a packing similar to that of Fig. 1, of slightly different size and shape applied to a goblet and usable for goblets, tumblers, jars and other articles;

15 Fig. 11 is a vertical medial section of another form of the packing applied to plates or saucers, shown therein, the said articles and packing being stacked and partly nested;

Fig. 12 is an elevation of a packing similar 20 to that of Fig. 11 as it is applied to bowls and various other articles of like general shape;

Fig. 13 is a vertical medial section of a packing similar to that shown in Fig. 12 applied to a cup;

25 Fig. 14 is a detached plaited portion of a packing unit embodying the improvements; and

30 Fig. 15 is a top perspective view of a packing embodying the improvements molded and adapted to be inverted to produce a conical form similar to that of Figure 11.

The packing unit shown in Figs. 1 to 9, inclusive, is substantially identical, but may have such variations in dimensions, shape and details as may be considered necessary or advisable to

35 better adapt it to variations in the articles to be packed, although this is not essential, as it will receive and securely hold and protect not only the particular articles illustrated but many others differing from them substantially. This

40 unit consists of a series of plaits or folds 1 of fibrous sheet material. The sheet material, however, is not first formed and then folded or plaited but is molded in substantially the form shown, preferably by the method known as the pulp sucking process, in which wire mesh or other foraminous forms are immersed in a bath containing wood pulp or other suitable fibres, while suction is exerted on one side of the mold or form to draw the fibres in the bath against

45 them and form a substantial coating thereon, after which the form, with the coating thereon, is removed from the bath and the coating taken off the form and dried. When the sheet thus formed is removed from the forming dies, and

50 while it is still in a wet and plastic state, the folds may be pressed together if desired to contract them and make the plaits sharper or more acute, or they may be stretched to some extent if such stretching is considered desirable for the

55 particular use to which the packing is to be put. In the illustrated fragment of the packing of Fig. 2, the fibre bath side is the upper side and the foraminous form side the lower side. It will be observed that the angle or fold at the bottom of each plait is thicker, as shown at 2. This results in a strengthening of the fold and an increased tendency to return to its normal state, and may be produced by increasing the area of

60 the suction openings in the form along these lines or in any other desired manner. The formation of the sheets in this manner produces a felted article in which the fibres are superposed and engage with one another in various positions, but in substantially their normal state, so that the sheet when thus formed is a sheet in which the

65 felted fibres are in normal position when the sheet is plaited as shown, and therefore tend always to give the sheet strength and resiliency and a constant tendency to return to its normal position when contracted or stretched.

70 The plaits or elastic ribs 1 are preferably tapered from one end to the other and provided with indentations or flattened portions 3, 3' 80 on their inner edges. They also have inward projections 4 at one end, and may have projections 5 of similar character at the opposite end as in Fig. 14, for the purpose of holding the articles packed therein and protecting them against injury by pressure or shocks directed against their ends. These projections may have 85 various forms, such variations being shown at 3 in Fig. 3, 7 in Fig. 12, and 8 in Figs. 10, 11, 13 and 14, and one or both ends may be inwardly turned on a curve of small radius as shown at 90 9 in Fig. 10.

95 The packing units shown in Figs. 11 to 13 are substantially the same, and one rib or plait thereof is shown in detail in Fig. 14. In Fig. 11 small plates or saucers are shown packed in this unit. This is accomplished by pressing the article into 100 the unit, thereby causing it to spread from a position similar to that shown in Fig. 13 to a sufficient diameter to receive the article, which is held therein by the tendency of the unit to return to its normal position and the engagement of the periphery of the article with the angular extensions 8. Any desired number of 105 relatively flat articles may be stacked and partly nested in their packing units. A packing unit of the size illustrated in Fig. 12 will receive and 110 hold plates of much greater diameter, and also bowls, vegetable dishes and teapots, whether they be circular, elliptical or of other form in cross section. The cup-holding unit shown in Fig. 13 is adapted to hold not only cups, saucers 115 and small plates, but such other articles as may be placed therein and confined by the inwardly projecting members 8. In the uses shown in 120 Figs. 11 and 13, and in all similar uses, the spreading of the upper edges of the unit surrounding its mouth and through which the article is inserted, causes a contraction and turning in of the lower edges, so that the article is gripped not only by the tendency of the plaits to contract laterally but by a certain pressure exerted by the 125 contracted lower ends.

130 In Fig. 15 a method of molding units such as those shown in Figs. 11 to 14, inclusive, is shown. In this method the unit is molded in reversed or inverted form, and after being molded is turned 135 inside out to the form shown in the said figures, which form it will constantly tend to maintain in use. The units of the said figures may also be molded substantially as shown in Fig. 13. This method of molding avoids the necessity of forming the unit by taking a flat sheet, such as that shown in Fig. 2, bending it into cylindrical or conical form and uniting the abutting edges. These abutting edges when a unit is made of a flat sheet may be joined by stitching, pasting, 140 stapling or interlocking. The joined ends or edges of the sheets are indicated at 10 in Figs. 8 and 9.

145 Whether the sheets of which the units are formed are molded as shown in Fig. 2 or as shown in Figs. 13 and 15, they may be stacked and nested for shipping and storage, so that they will occupy a minimum of space, when not in use.

150 As most articles to be packed have curved outlines, and it is desirable in all cases to have as

close a contact as possible near the ends of the packing unit the plaits or elastic ribs of the said units are usually curved to a greater or lesser extent from end to end, so that the normal diameter of the finished unit is greater at its middle portion than at its ends. The ribs may also have any other desired contour and may be made of various sizes to meet conditions of use. They may also be made of any suitable material and by any satisfactory method, the method and material herein described being merely considered the most suitable for the purpose. Other modifications in the form material and method of manufacture may be made without departing from the scope of the invention.

The term "offset" as employed in the claims contained herein refers to any deviation from a straight line whether it be gradual, as in the case of a curve, or whether it be abrupt as in the case of a pronounced angular divergence. It is understood that any departure from a straight line is embraced within this term in the claims.

The packing of the present improvements is peculiar and has many uses and advantages. It will be seen that it requires no wrapping or tying but holds itself in position and holds the article packed without the aid of any other means or instrumentality; that it exerts constant pressure on the article packed by its resiliency and its tendency at all times to return to normal position; that each unit will accommodate, hold and protect a variety of articles, and that it can be made in finished condition for use by a simple pulp molding operation, without the use of tools, machinery or labor. It can also be made in various sizes and shapes, while retaining all the peculiar characteristics and advantages just mentioned.

The packing saves labor, permits the employment of unskilled labor even in the packing of the most costly fragile articles and prevents breakage. It also economizes space and permits the packing of sets or lots in smaller cases or other shipping containers. In packing individual articles in the units it is only necessary to insert each article in its packing unit by pressing it through the opening in one end thereof and into the interior and permitting the packing to close on it and to contract its said opening so that it is securely enclosed and held. When a shipping case is packed the separate articles are first inserted in their individual packing units and these units with the articles in them then placed in the case in close contact with one another.

Another advantage resides in the fact that articles once placed in the units need no other packing in their passage from maker to ultimate consumer or user through wholesalers, distributors or other middlemen and retailers, and that they can be removed for examination and replaced by any person of ordinary intelligence, and can be carried or otherwise transported even by careless persons without danger of breakage.

What I claim is:

1. A packing unit comprising a sheet of material having a series of uniform folds or plaits, said plaits having a series of integral plaits or projections of greater depth than the first named plaits and hinge means in different planes uniting plaits of each series.

2. In an unbroken plaited packing sheet, means for engaging an article for holding it relative to the plaits comprising a plurality of projections

integral with and extending to planes beyond the plaits of the sheet.

3. A fluted packing unit made of flexible but relatively resistant material comprising a sheet made of fibrous material having a series of plaits in juxtaposition extending between opposite sides of the sheet, said plaits, along their longitudinal axes, being constructed in bent form in a manner to produce an offset in the sheet before its application to an article, so that when the sheet is made into a packing or protecting jacket it will conform at least partly to the shape of an article to be received therein.

4. A fluted packing unit made of flexible but relatively resistant material comprising a sheet made of fibrous material having a series of plaits in juxtaposition extending between opposite sides of the sheet, said plaits, along their longitudinal axes, being constructed in bent form in a manner to produce an offset in the sheet before its application to an article, said plaits having laterally extending projections adjacent one end of the plaits, so that when the sheet is made into a packing or protecting jacket it will conform at least partly to the shape of an article to be received therein and will hold itself thereon.

5. A fluted packing unit made of flexible but relatively resistant material comprising a sheet made of fibrous material having a series of plaits in juxtaposition extending between opposite sides of the sheet, said plaits, along their longitudinal axes, being constructed in bent form in a manner to produce an offset in the sheet before its application to an article, said plaits having a series of laterally extending projections adjacent each end of the plaits, so that when the sheet is made into a packing or protecting jacket it will conform at least partly to the shape of an article to be received therein and will hold itself thereon.

6. A fluted packing unit made of flexible but relatively resistant material comprising a sheet molded from fibrous material having portions of its entire area provided with molded plaits extending between opposite sides of the sheet, said plaits having portions preformed in bent shape in a direction along their longitudinal axes and in such manner as to offset the sheet out of a single plane, whereby the sheet, when made into a jacket-like wrapper, will conform generally to the shape of an article to be received therein.

7. A fluted packing unit made of yieldable material comprising a sheet molded from fibrous material having a series of juxtaposed plaits extending between opposite sides thereof, said plaits being preformed in irregular contour in the direction of their longitudinal axes so as to produce an offset in the sheet before its application to an article, so that the plaits will conform at least partly to the shape of an article to be packed when the sheet is made into a wrapper.

8. A molded paper pulp packing unit comprising a sheet of yieldable pulp material having a series of juxtaposed plaits running from one side of the unit to the opposite side, said plaits being molded in curved form in a direction longitudinally of the plaits, and in such manner as to offset the sheet out of a single plane.

9. A molded paper pulp packing unit comprising a sheet of yieldable pulp material having a series of juxtaposed plaits running from one side of the unit to the opposite side, said plaits being molded in curved form in a direction longitudinally of the plaits and in such manner as to offset the sheet out of a single plane, said plaits having

- molded projections extending beyond the plane of the plaits.
10. A fluted packing unit made of yieldable pulp material comprising a sheet having a series of juxtaposed plaits extending from one side to an opposite side, the edge lines of the plaits at one side of the sheet being substantially greater in their total length than the edge lines at the other side of the sheet.
11. A fluted packing unit made of flexible but relatively resistant material comprising a sheet having substantially its entire area provided with plaits extending from one side to an opposite side, the edge lines of the plaits at one side of the sheet being substantially greater in their total length than the edge lines at the other side of the sheet.
12. A fluted packing unit made of yieldable pulp material comprising a sheet having a series of juxtaposed plaits extending from one side to an opposite side, said plaits having a bent shape in the direction of their longitudinal axes, the edge lines of the plaits at one side of the sheet being substantially greater in their total length than the edge lines at the other side of the sheet.
13. A fluted packing unit made of yieldable pulp material comprising a sheet having a series of juxtaposed plaits extending from one side to an opposite side, said plaits being formed deeper at one side than at the other side, the edge lines of the plaits at one side of the sheet being substantially greater in their total length than the edge lines at the other side of the sheet.
14. A fluted packing unit made of yieldable pulp material comprising a sheet having a series of juxtaposed plaits extending from one side to an opposite side, said plaits having an arcuate shape in the direction of their longitudinal axes and being formed deeper at one side than at the other side, the edge lines of the plaits at one side of the sheet being substantially greater in their total length than the edge lines at the other side of the sheet.
15. A fluted packing unit made of flexible and relatively resistant fibrous material comprising a sheet having a series of juxtaposed plaits extending from one side to an opposite side, said plaits, in the direction of their longitudinal axes, being curved from one side of the sheet toward the opposite side and said plaits being correspondingly graduated in depth from one side toward the opposite side, the edge lines of the plaits at one side of the sheet being substantially greater in their total length than the edge lines at the other side of the sheet.
16. A fluted packing unit made of yieldable pulp material comprising a sheet having a series of juxtaposed plaits extending from one side to an opposite side, said plaits having laterally extending projections adjacent one end of the plaits, the edge lines of the plaits at one side of the sheet being substantially greater in their total length than the edge lines at the other side of the sheet.
17. A fluted packing unit made of yieldable pulp material comprising a sheet having a series of juxtaposed plaits extending from one side to an opposite side, said plaits having an arcuate shape in the direction of their longitudinal axes, and having laterally extending projections adjacent one end of the plaits, the edge lines of the plaits at one side of the sheet being substantially greater in their total length than the edge lines at the other side of the sheet.
18. A plaited packing unit in the form of a hollow sleeve-like jacket formed of flexible relatively resistant fibrous material, said jacket having a series of juxtaposed plaits provided around the jacket and extending from one end to an opposite end of the jacket, the plaits at one end having an inward arcuate shape in the direction of their longitudinal axes and the edge lines of the plaits at one end of the jacket being substantially greater in their total length than the edge lines at the other end of the jacket whereby one end of the jacket is maintained more contracted than the opposite end.
19. A plaited packing unit in the form of a hollow sleeve-like jacket for fragile articles comprising a sleeve member having a series of plaits extending from one end to an opposite end for encompassing the sides of an article, and a second series of plaits integral with the first named plaits at one end of the sleeve member, said second series of plaits being offset inwardly beyond the inner limits of the first named plaits whereby a plaited annulus is formed of less diameter than the sleeve member for providing an enclosure for an end edge of an article packed within the sleeve member.
